(57) **CLAIM**

We claim the ornamental design for a mobile device case, as shown and described.

DESCRIPTION

FIG. 1 is a perspective view of a mobile device case;
FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof; and,

FIG. 7 is a right-side elevation view thereof.

Broken lines are used to illustrate unclaimed portions of the mobile device case; broken lines form no part of the claimed design.
